(57) **CLAIM**

The ornamental design for a dual chamber venous access port, as shown and described.

DESCRIPTION

FIG. 1 is an isometric view of a dual chamber venous access port showing my new design;

FIG. 2 is a right side view thereof, the left side being a mirror image;

FIG. 3 is a top view thereof;

FIG. 4 is a bottom view thereof;

FIG. 5 is a distal end view thereof; and,

FIG. 6 is a proximal end view thereof.
